UNITED STATES PATENT OFFICE.

HOWARD T. HALLOWELL, OF PHILADELPHIA, PENNSYLVANIA.

SHAFT-HANGER.

1,320,046.

Specification of Letters Patent. Patented Oct. 28, 1919.

Application filed March 26, 1913, Serial No. 756,927. Renewed May 29, 1918. Serial No. 237,366.

To all whom it may concern:

Be it known that I, HOWARD T. HALLOWELL, a citizen of the United States, residing in Philadelphia, Pennsylvania, have invented certain Improvements in Shaft-Hangers, of which the following is a specification.

My invention relates to shaft supporting structures; and the object of my invention is to provide hanger structures of substantially the same type illustrated in the patent of Harald F. Gade, No. 1,165,332, dated December 21, 1915, in which are shown shaft hangers constructed of commercial rolled metal sections. In the present invention, however, while I have shown types of hangers made of commercial rolled sections, I have also shown other types made of pressed up sheet metal suitably reinforced as desired, and, in all instances, I have shown special forms of connecting and bracing members for the legs of the hangers, which connecting and bracing members are made in various forms by shaping and pressing up sections of sheet metal.

These and other features of my invention will be more fully described hereinafter, reference being had to the accompanying drawings forming part thereof, in which:

Figure 1, is a view of a hanger within the scope of my invention, the legs of which are made of sheet metal pressed into shape;

Fig. 2 is a view showing the shape of one end of a blank from which a hanger leg is made;

Figs. 3 and 4, are, respectively, a front elevation and an edge view of the finished hanger leg end prior to the bending of the same to form a foot;

Fig. 5, is a sectional view on the line 5—5; Fig. 8;

Fig. 6, is a sectional view on the line 6—6; Fig. 1;

Figs. 7, 8 and 9, are sectional views illustrating types of commercial metal and shaped sheet metal which may be employed in the formation or manufacture of shaft hanger legs of this general type;

Fig. 10, is a sectional plan view on the line 10—10, Fig. 1;

Figs. 11 and 12, are, respectively, a plan of a blank and a side elevation of a finished connecting element made therefrom, which connecting elements are employed in pairs and are shown in Figs. 1 and 10;

Fig. 13, is a view similar to Fig. 10, showing retaining clips for the ends of the con-

necting elements illustrated in Figs. 1, 10 and 12;

Fig. 14, is a perspective view of a retaining clip;

Figs. 15 and 16, are views similar to Fig. 1, showing other forms of shaft hangers within the scope of my invention;

Fig. 17, is a plan view showing a blank of a modified form of connecting member;

Figs. 18, 19 and 20, are, respectively, a plan view, a side elevation, and a cross-sectional view of a connecting member made from the blank shown in Fig. 15;

Fig. 21, is a sectional plan view of shaft hanger legs made from a metal section such as shown in Fig. 9, showing another form of connecting member therefor;

Fig. 22, is a plan view of a blank from which the connecting member shown in Fig. 21 is made;

Fig. 23, is a side elevation of another form of connecting member employing a plurality of parts;

Fig. 24, is an enlarged sectional view on the line 24—24, Fig. 23;

Fig. 25, is a sectional view similar to Fig. 24 showing a slightly modified construction;

Fig. 26, is a fragmentary view of the lower end of a shaft hanger leg made from a metal section such as shown in Fig. 9, and

Fig. 27, is a cross-sectional view on the line 27—27, Fig. 26.

In the form of structure shown in Fig. 1, I have illustrated a shaft hanger having side supporting members made from a V-shaped metal section, which may be sheet metal pressed into the desired V-shaped cross section or a commercial angle section, and each of these side supporting members is bent to provide a leg portion 1; a journal-box supporting portion 2, and a foot 3, integral with said leg portion. The upper end of the side supporting members from which the feet of the hanger legs are formed is reinforced by doubling the metal composing the same, and the shape of the said upper end of the blank of the side supporting member is shown in Fig. 2. The legs are shaped in substantially the same manner as in the application before referred to; the metal being gradually flattened from the point α and forming the broad supporting feet 3 at the ends thereof.

In manufacturing legs provided with the reinforced feet, the narrow tongue 1^a is bent back upon the major portion of the leg, and

the edges of the latter for a certain length are bent up to form flanges 1^b to engage said tongue, which is then secured to the leg by rivets 1^c. A bolt aperture 3^a is formed in 5 the doubled end of the leg, and then it is bent to the shape shown in Fig. 1, forming a foot. In some instances, the central portion of the foot adjacent the bolt aperture may be depressed as at 3^b for added strength. 10 In the form of hanger shown in Fig. 1, I employ a special form of connecting or bracing member 5 for the legs, which is duplex in character; the halves being divided on a vertical line. The blank for forming 15 one-half of said bracing member is shaped as shown in Fig. 11, and this is pressed up into the shape shown in the side elevation, Fig. 12, providing ears 6 which are disposed at an angle with respect to the longitudinal 20 portion of said connecting or bracing member, and these ears are secured to the hanger leg by rivets 7. To avoid any danger of the metal of the leg spreading at this point, I may provide retaining means in the form of 25 clips 8, as illustrated in Figs. 13 and 14, which are held to the hanger legs and connecting and bracing member by the rivets 7. The portion of the blank forming the horizontal walls of the connecting or bracing 30 member is notched at 9, and when the two halves of the bracing member are brought together, these notches provide apertures for the passage of vertical positioning bolts 10, shown by dotted lines, when it is desired 35 to use the latter.

The lower portions of the shaft hanger legs are shaped as shown in Fig. 6, and the bottom ends are squared as indicated at 11.

Connecting the squared ends of the legs is 40 a pressed sheet metal cradle structure 12 having embracing end walls 13 to engage the squared ends 11 of the legs, and this cradle structure is secured to the legs by bolts 14. This cradle structure is provided with ends 45 15 continuous with the bottom thereof, which engage the outer walls of the legs, and this bottom is preferably socketed at the center, as indicated at 16, to form seats for nuts 17 and 18, and apertured for the passage of the 50 lower vertical positioning bolt, when the latter is employed.

Figs. 7, 8 and 9, illustrate various forms or sections of commercial metal or sheet metal which may be employed for the legs of the 55 hanger. With this form of hanger, I also preferably provide a bracing member 20 connecting the legs in substantially the plane of the feet, which may be secured to the legs by rivets 21.

60 In Fig. 15, I have shown a hanger structure substantially like that shown in Fig. 1, excepting certain modifications or changes in the shape of the legs. The lower ends of the legs below the journal-box supporting 65 portion are reduced in size and shaped as at

11^a for the reception of a lower connecting member 12^a, of the same contour as the legs, which may be secured to said legs by bolts and nuts 22 and 22^a; filler pieces or blocks 23 being employed to overlie the outer wall 70 of the cradle structure. This form of hanger is provided with the usual adjustable positioning bolts 24 for a journal-box; with a cross piece or bracing member 5^a of a type hereinafter described, and with a bracing 75 member 20, connecting the legs in the plane of the feet.

In Fig. 16, I have shown another form of hanger embodying my invention in which a J-shaped support for the journal-box is provided. In this instance, the J-shaped support and one leg are formed from a single continuous piece while the other leg has a horizontal portion 5^b crossing above the journal-box and joined to the continuous leg 85 by rivets 25. In such structure, I may provide upper and lower positioning bolts 10, as indicated by the dotted broken lines, for the journal-box, as well as the horizontally disposed positioning bolts 24. This hanger 90 is also provided with a bracing member 20 connecting the legs in the plane of the feet.

In Fig. 17, I have shown a shape or form of blank from which the form of bracing and connecting member shown in use in 95 Figs. 15 and 16, and within the scope of my invention may be made. This blank is recessed at 26 on both sides, and slit at *a* and *b*; the slits *b* being at right angles to the slits *a*. It is then pressed into the shape shown 100 in Figs. 18, 19 and 20, providing a series of ears 6^a whereby it may be riveted to the hanger, and is apertured at 9^a for the passage of a positioning bolt, such as 10.

In Fig. 21, I have shown a sectional plan 105 view of the legs of a type of hanger such for instance as illustrated in Figs. 1 and 15, in which the legs are made from a metal section such as shown in Fig. 9. These legs are spaced apart and secured together by a 110 connecting member 5^b which is also duplex in character; that is to say, it is made of upper and lower members each of the same shape; the complete structure being shown in elevation in Fig. 23, and in cross section 115 on a larger scale in Fig. 24, such view being on the line 24—24, Fig. 23. Fig. 22 shows the blank from which the sections of this bracing or connecting member are made.

Fig. 25 shows a modified construction in 120 which the walls of the half sections 5^c instead of abutting each other on a median line, are lengthened and pass within each other on opposite sides. These forms of bracing or connecting members are provided 125 with ears 6^c, which are riveted to the hanger legs.

In Fig. 26, I have shown the construction of the lower end of the hanger leg shown in Fig. 21, to which a lower connecting cross- 130

member or cradle structure 12^c is connected; Fig. 27 being a sectional view on the line 27—27, Fig. 26.

I claim:

- 5 1. A shaft hanger comprising a pair of legs made of sheet metal having a central portion substantially V-shape in cross section and providing a pair of flanges, said legs having flattened upper ends shaped to 10 form feet integral therewith, and a plurality of sheet metal members between said legs spacing and connecting the same, one of said connecting members being intermediate the top and bottom of the hanger and 15 forming a substantially central brace for the legs, said member having ends shaped to fit the flanges of the V-shaped portions of the legs, with means for securing said ends to the legs, in combination with means 20 for securing a journal-box in position, said means being carried by the legs of the hanger and a plurality of connecting members therefor.

2. A shaft hanger comprising a pair of legs made of sheet metal each having a substantially central portion substantially V-shape in cross section with a flattened upper end into which the V-shaped portion or flange gradually merges and a U-shaped 30 lower end merging with the portion of V-shape, said upper ends being shaped to form feet and reinforced by doubling the metal of the legs upon itself, a sheet metal member connecting the U-shaped lower ends 35 of the legs, a sheet metal member forming a substantially central brace and having ends shaped to fit the V-shaped portion of said legs, with means for securing the ends of said brace to the legs, in combination with 40 bolts for securing a journal-box in position; said bolts being carried by the legs of the hanger and a plurality of connecting members therefor.

3. A shaft-hanger comprising legs made 45 of sheet metal bent or upset to V-shape, with flattened upper ends, said ends being reinforced and bent to form feet integral with said legs, a sheet metal member spacing and connecting the angular portion thereof, said 50 member having ends shaped to fit the inner portions of said legs with ears secured to said legs, in combination with means passing through the walls of the legs to secure a journal-box in position.

- 55 4. A shaft hanger comprising legs made of metal having substantially central portions V-shape in cross section with flattened upper portions, the ends of which are shaped to form feet integral with said legs, sheet 60 metal bracing means spacing and connecting the legs at the V-shaped portion of the same, said bracing means being in a plurality of sections each having ears for engagement with the V-shaped portions of the legs, 65 means for securing said ears to the legs, in

combination with bolts passing through the walls of the legs to secure a journal-box in position.

5. A shaft hanger comprising a pair of side supporting members composed of sheet metal bent to form legs having a channel-shaped lower portion, a V-shaped body and flattened feet, said feet being reinforced by bending the metal of the same upon itself between integral side flanges, a sheet metal brace having ends fitting the legs of such structure, said brace having ears at its ends, and means for securing said ears to the legs of the shaft hanger.

6. A shaft hanger comprising a pair of sheet metal legs, each being V-shape for a portion of its length, reinforced feet comprising a plurality of layers of folded metal, sheet metal bracing means for the legs of such structure, said brace being made in two parts each having integral ears shaped to lie against the inner walls of the V-shaped portions of the legs, and means for securing said ears to the legs.

7. A shaft hanger comprising a pair of legs each made of a single section of sheet metal having an angular portion, each of said legs having its upper end shaped to form a foot integral with said leg, said feet being reinforced by bending the metal upon itself, a channel-shaped cross-brace in the same plane as said feet, a sheet metal spacing and connecting member intermediate the upper and lower ends of said legs and made in a plurality of parts, each part having side walls with horizontal flanged portions integral therewith and end portions of a greater width than said side walls, said end portions terminating in ears shaped to engage the angular walls provided by said legs, and means for securing the ears of said connecting member parts to the legs, the horizontal portions of said connecting member parts being apertured for the passage of bolts for positioning a journal-box 110 with respect to said shaft hanger.

8. A shaft hanger comprising a pair of legs each made of a single section of sheet metal having an angular portion and shaped to form a reinforced foot integral with said leg, a sheet metal spacing and connecting member for said legs made in a plurality of parts, each part having side walls and end portions terminating in ears shaped to engage the angular walls provided by said legs, means for securing the ears of said connecting member to the legs, and tie members secured to the angular walls of said legs at each end of the connecting member and overlying said ears.

9. A shaft hanger comprising legs made of sheet metal having intermediate portions V-shape in cross section with flattened upper ends forming feet integral with said legs and reinforced by bending the metal of the

- same back upon itself, a sheet metal member spacing and connecting the legs at the V-shaped portion of the same, said sheet metal member having upstanding ears engaging the inner walls of said V-shaped portions, means for securing said ears to the legs, and tying means for said ears, in combination with means carried by the legs to position a journal-box.
10. A shaft hanger comprising a pair of side supporting members shaped to form legs, each of said legs having a U-shaped lower end, a flattened foot at the upper end and a V-shaped body intermediate said upper and lower ends, said feet being integral with the legs and reinforced by doubling the metal upon itself, a sheet metal brace spacing and connecting the legs of such structure at the V-shaped portion of the same, said brace having ears, means for securing the ears of said brace to the angular walls of said legs, and tying members overlying said ears, said tying members being secured to the legs by the fastening means securing the ears of the brace.
11. A shaft hanger comprising a pair of legs V-shaped in cross-section for a portion of their length, reinforced feet integral with said legs, a sheet metal brace for said legs, said brace having integral ears bent to lie against the inner walls of the V-shaped portions of the legs, rivets for securing said ears to the legs, and tie members carried by each leg, said tie members overlying said ears and designed to prevent spreading of the angular walls of said legs.
12. A shaft hanger including a pair of sheet metal legs V-shaped for a portion of their length, integral feet carried by said legs and reinforced by doubling the metal upon itself, a sheet metal brace for the legs of such structure intermediate the upper and lower ends of the same, said brace having ears bent to engage the V-shaped portions of the legs, means for securing the ears of said brace to the legs, a hollow sheet metal connecting member embracing the lower ends of said legs, and means detachably securing said connecting member thereto, said lower ends of the legs being of U-shape, and the sheet metal connecting member therefor being substantially U-shape in cross section.
13. In a shaft hanger, a pair of legs, each having a portion V-shape in cross section, a bracing member for the legs made of sheet metal pressed into shape and having ears for engagement with the V-shaped portions of said legs, rivets securing said ears to the legs, and wedge-shaped tie members at the ends of said bracing member and adjacent the legs, said tie members overlying said ears and held to the legs by the rivets securing the ears thereto.
14. A shaft hanger comprising a pair of legs made of sheet metal each having a substantially central portion substantially V-shape in cross section with a flattened upper end into which the V-shaped portion gradually merges and a U-shaped lower end merging with the portion of V-shape, said upper ends being shaped to form reinforced feet, a sheet metal member connecting the U-shaped lower ends of the legs, a sheet metal member forming a substantially central brace and having wedge-shaped ends to fit the V-shaped portions of said legs, with means for securing the ends of said brace to the legs, in combination with bolts for securing a journal-box in position; said bolts being carried by the legs of the hanger.
15. A shaft hanger comprising legs made of sheet metal bent or upset to V-shape, with flattened upper ends; said ends being bent to form feet integral with said legs, a sheet metal member spacing and connecting the angular portion of the legs, said member having ends shaped to fit the V-shaped portions of said legs with ears secured to said legs, in combination with means passing through the walls of the legs to secure a journal-box in position.
16. A shaft hanger comprising a pair of side supporting members composed of sheet metal bent to form legs having a channel-shaped lower portion, a V-shaped body and flattened feet, a sheet metal brace having ends fitting the legs of such structure; said brace having ears at its ends, and means for securing said ears to the legs of the shaft hanger.
17. A shaft hanger comprising a pair of sheet metal legs, each being V-shape for a portion of its length, reinforced feet comprising a plurality of layers of folded metal, sheet metal bracing means for the legs of such structure, said brace having integral ears shaped to engage the walls of the V-shaped portions of the legs, and means for securing said ears to the legs.
18. A shaft hanger comprising a pair of legs each made of a single section of sheet metal having an angular portion, each of said legs having its upper end shaped to form a foot integral with said leg; said feet being reinforced, a channel-shaped cross-brace in the same plane as said feet, a sheet metal spacing and connecting member intermediate the upper and lower ends of said legs; said member having side walls with horizontal flanged portions integral therewith and end portions of a greater width than said side walls, said end portions terminating in ears shaped to engage the angular portions of said legs, and means for securing the ears of said connecting member to the legs, the horizontal portions of said connecting member being apertured for the passage of bolts for positioning a journal-box with respect to said shaft hanger.

19. A shaft hanger comprising a pair of legs each made of a single section of sheet metal having an angular portion and shaped to form a reinforced foot integral with said leg, a sheet metal spacing and connecting member for said legs having side walls and end portions terminating in ears shaped to engage the angular portions of said legs, means for securing the ears of said connecting member to the legs, and tie members secured to the angular portions of said legs at the ends of the connecting member and overlying said ears.
20. A shaft hanger comprising legs made of sheet metal having intermediate portions V-shape in cross section with flattened upper ends forming feet integral with said legs, a sheet metal member spacing and connecting the legs at the V-shaped portions of the same, said sheet metal member having upstanding ears in wedge-shape formation to engage the walls of said V-shaped portions, means for securing said ears to the legs, and tying means for said ears, in combination with means carried by the legs to position a journal-box.
21. A shaft hanger including a pair of sheet metal legs V-shaped for a portion of their length, reinforced feet integral with said legs, a sheet metal brace for the legs of
- such structure intermediate the upper and lower ends of the same, said brace having ears bent to engage the V-shaped portions of the legs, means for securing the ears of said brace to the legs, a hollow sheet metal connecting member embracing the lower ends of said legs, and means detachably securing said connecting member thereto, said lower ends of the legs being of U-shape, and the sheet metal connecting member therefor being substantially U-shape in cross section.
22. In a shaft hanger, a pair of legs, each having a portion V-shape in cross section, a bracing member for the legs made of sheet metal pressed into shape and having ears for engagement with the V-shaped portions of said legs, means for securing the ears of said bracing member to the legs, and wedge-shaped tie members at the ends of said bracing member and adjacent the legs, said tie members overlying said ears and held to the legs by the means securing the ears thereto.

In testimony whereof, I have signed my name to this specification, in the presence of two subscribing witnesses.

HOWARD T. HALLOWELL.
